(57) **CLAIM**

The ornamental design for a chair, as shown and described.

DESCRIPTION

FIG. 1 is a front, left perspective view of a chair embodying my new design;

FIG. 2 is a left side elevational view thereof, the right side elevational view being a mirror image thereof;

FIG. 3 is a front elevational view thereof;

FIG. 4 is a rear elevational view thereof; and,

FIG. 5 is a top plan view thereof.

The broken line representations of bottom front leg supports in FIGS. 1-3, 5; a cross bar leg support in FIGS. 1, 3, 4; wheels in FIGS. 1-5; upholstery ends in FIGS. 1-2 are for the purpose of illustration only, and form no part of the claimed design.
